(57) **CLAIM**

The ornamental design for an electronic device holder for a tripod stand, as shown and described.

DESCRIPTION

FIG. 1 is a top perspective view of an electronic device holder for a tripod stand, showing our new design;

FIG. 2 is an exploded top perspective view thereof;

FIG. 3 is an exploded rear perspective view thereof;

FIG. 4 is an exploded front elevational view thereof;

FIG. 5 is an exploded rear elevational view thereof;

FIG. 6 is an exploded left-side elevational view thereof, the right-side elevational view being a mirror image thereof;

FIG. 7 is an exploded top plan view thereof; and,

FIG. 8 is an exploded bottom plan view thereof.

The broken lines in FIG. 1 showing a tripod and an electronic device show environmental matter that forms no part of the claimed design. The remaining broken lines depict portions of the electronic device holder for a tripod stand that form no part of the claimed design.

1 Claim, 8 Drawing Sheets
